UNITED STATES PATENT OFFICE.

JAMES T. FIELDS, OF ELGIN, ILLINOIS.

IRONING-TABLE.

1,029,056.

Specification of Letters Patent. Patented June 11, 1912.

Application filed November 6, 1911. Serial No. 658,761.

To all whom it may concern:

Be it known that I, JAMES T. FIELDS, a citizen of the United States, residing at Elgin, in the county of Kane and State of Illinois, have invented certain new and useful Improvements in Ironing-Tables; and I do declare the following to be a full, clear, and exact description of the invention, such as will enable others skilled in the art to which it appertains to make and use the same.

This invention is an ironing table such as may be used in the laundry or at any place where it can be attached to the edge of any ordinary table top, and the object of the same is to construct such a table so that the ironing board will project far over the legs or support and permit a long article such as a full length skirt to be passed over said board to be ironed.

Another object is to construct the board so that this table may be set up and attached to an ordinary table or shelf by but a single movement of the support, and to render the clamping lever of the support adjustable so that it will engage a table top of greater or lesser thickness.

With these objects in view the invention consists in the details of construction herein-after more fully described and claimed and as shown in the drawings wherein—

Figure 1 is a plan view of this improved ironing table set up, and Fig. 2 is a side elevation thereof; Fig. 3 is an end view of the same; Fig. 4 is a perspective view of the ironing table folded, viewing the same from the under side; Fig. 5 is a perspective detail of the clamping lever; and Fig. 6 a perspective detail of the adjustable foot.

In the drawings the letter I designates the top of this table which is an ordinary ironing board (preferably covered with cloth although the same is not shown), and the letter T designates the top of an ordinary table such as is generally found in the kitchen or the laundry, or it may be the edge of a shelf or some other member of proper height to support the ironing board I. When the devices hereinafter described are constructed as set forth and attached to this ironing board, the latter becomes an ironing table adapted to be clamped to the edge of the table top T.

Coming now more particularly to the present invention, the top I is provided across its bottom with two transverse cleats 1 and 2, preferably secured thereto by screws so as

to prevent warping or cracking of the board, and through the cleat 1 which is nearest the clamping end of the board, is passed a bolt 3.

The numeral 4 designates the clamping lever, having in its body a slot 5 for the loose passage of said bolt so that the lever may rock over the cleat 1 above the nut at the lower end of the bolt as will be clear. 60 One end of this lever may be provided with teeth or spurs 6 projecting upward and adapted to engage beneath the edge of the table top T if desired, and the other end of the lever is reduced and formed into an elongated tongue 7 which has a notch 8 in its outer extremity.

The numeral 10 designates the leg of this improved ironing table and 11 is the foot thereof. The latter has an upright slot 12 75 in its body adjustably engaged by two or more bolts 13 passing through the lower end of the leg, whereby the total length of the leg and foot may be adjusted to correspond with the height of the table top T to which this device is to be attached. When in folded condition as seen in Fig. 4, the entire leg and foot is supported beneath the top I by hook and eye connection 14, 15.

The upper end of the leg is forked as at 85 16, and between the arms of the fork the tongue 7 of the clamping lever is pivoted by a transverse pin or bolt 17 at such a distance from the rounded extremities 18 of the fork arms that the latter will bind beneath the table top I as seen in Fig. 2. The clamping lever 4 rocks over the cleat 1 and pinches the table top T, and at this time the upper end of the fork comes against the cleat 2 as therein shown and holds the 95 leg upright. A vertical guide pin 19 depends from this cleat and through the notch 8 in the clamping lever plays freely over it so that its inner end may rise and fall but may not move laterally of the board, and this guide therefore keeps the leg centered beneath said board. The depth of the fork 16 is sufficient to permit said pin 19 to be housed therein when the parts are folded as seen in Fig. 4.

The parts of this device are of wood as far as possible, with hardware members such as may be purchased in the open market. The use of ironing tables of this character is too well known to need repetition here. 110 By adjusting the nut on the bolt 3 the clamping member 4 may be set for table

tops of different thicknesses, and this can be done without disturbing the connection between its inner end and the upper end of the leg. The foot 11 may be adjusted by means 5 of the bolts 13 to cause the top I to stand level when projecting from the table top T. But especial attention is directed to the particular hinge connection between the upper end of the leg and the inner end of the 10 lever—a connection which permits the leg to be stood vertical with its upper extremity resting against the inner cleat 2 to steady it in place, or to lie horizontal against the lower face of the top I and to be hooked 15 into place as shown in Fig. 4, and yet in either position or when passing from one position to the other the guide pin 19 engaging the notch 8 keeps the lever 4 and the leg 10 nicely centered along the under 20 side of the top I. The proportions and exact details of parts may be left to the manufacturer.

What is claimed as new is:

1. In an ironing table, the combination 25 with the top having two cleats along its lower face near its inner end, a bolt depending from the outer cleat, and a guide pin depending from the inner one; of a clamping lever having a slot in its body engaging said bolt and its inner end reduced to form a tongue and the inner extremity of said tongue notched and loosely engaging said 30 guide pin, a leg having a forked upper end mounted astride said tongue and the fork

arms provided with rounded extremities 35 adapted to contact with the lower side of said top, a transverse pivot through said arms and tongue, an adjustable foot at the lower end of the leg, and a hook and eye connection between said leg and top. 40

2. In an ironing table, the combination with the top having a transverse cleat along its under side, a guide pin depending from said cleat, and a clamping lever fulcrumed to the lower side of said top between the extremity of the latter and said cleat and having a notch in its inner extremity loosely engaging said guide pin; of a leg having a forked upper end mounted astride the inner 45 end of said lever, a transverse pivot through the lever and fork arms in such position that when the leg is upright the extremities of said arm engage beneath the top and against one edge of said cleat and the inner end of the lever is depressed out of contact 50 with said cleat, the length of said fork arms being sufficient to permit the notch between them to pass over said pin when the leg is folded upward against the table top, and means for holding it in this position. 55

In testimony whereof I have hereunto set my hand in presence of two subscribing witnesses.

JAMES T. FIELDS.
